CLAIM

I claim the ornamental design for pedestal-type sink, as shown and described.

DESCRIPTION

FIG. 1 is a perspective view of a pedestal-type sink showing my new design;

FIG. 2 is a front elevational view thereof;

FIG. 3 is a right side elevational view, the opposite side being a mirror image thereof;

FIG. 4 is a rear elevational view thereof;

FIG. 5 is a top plan view thereof;

FIG. 6 is a bottom plan view thereof;

FIG. 7 is a cross-sectional view taken along line 7—7 in FIG. 5; and,

FIG. 8 is a cross-sectional view taken along line 8—8 in FIG. 5.
